S. A. COWART.
WAGON STANDARD.
APPLICATION FILED AUG. 26, 1912.

1,061,224.

Patented May 6, 1913.

UNITED STATES PATENT OFFICE.

STEPHEN A. COWART, OF MIDLOTHIAN, TEXAS.

WAGON-STANDARD.

1,061,224.

Specification of Letters Patent.

Patented May 6, 1913.

Application filed August 26, 1912. Serial No. 717,044.

To all whom it may concern:

Be it known that I, STEPHEN A. COWART, a citizen of the United States, residing at Midlothian, in the county of Ellis and State 5 of Texas, have invented certain new and useful Improvements in Wagon-Standards, of which the following is a specification.

My invention relates to standards for wagons, and the object is to provide standards which are strong and durable and which are adjustable to any size bolster and adjustable to different positions on a bolster to make the width between the standards wider or narrower and which can be easily and 15 quickly mounted on a bolster and which do not require the cutting of large openings in the bolster, as the standards do not penetrate the bolster.

Other objects and advantages will be fully 20 explained in the following description and the invention will be more particularly pointed out in the claims.

Reference is had to the accompanying drawings which form a part of this application and specification.

Figure 1 is a side elevation of a standard attached to a bolster. Fig. 2 is a plan view of the same with the rings omitted. Fig. 3 is a side elevation of a standard attached to 25 a bolster, the shape of the standard being slightly varied and showing a variation in the braces used. Fig. 4 is a plan view of the same with the rings omitted. Fig. 5 is a side elevation mounted on a bolster and 30 showing another variation in the braces used. Fig. 6 is an edge view of the standard, a part being broken away, looking toward the end of the bolster. Fig. 7 is a plan view of one of the braces shown in Figs. 5 and 6. Fig. 8 is a plan view of one of the braces 35 shown in Figs. 1 and 2.

Similar characters of reference are used to indicate the same parts throughout the several views.

The standard has a body 1 and a base 2 made integral therewith. The standard has flanges 3 on the inner sides and beads 4 on the outer edge formed integral therewith. The standards are preferably made of malleable cast iron. The base 2 rests flat on the bolster 5 and is attached thereto by a bolt 6 with a nut 7. The standard is further attached to the bolster by braces 8, a brace being placed on each side of the standard. A 45 single bolt 9 with a nut 10 attaches both braces 8 to the bolster. The braces 8 are

extended inwardly to make the braces more potent and also to make the horizontal bolt 9 lie out of the path of the vertical bolts 11. Each brace 8 has a vertical portion which 50 engages the side of the bolster and a horizontal portion which engages the base 2 of the standard. Each brace 8 has a slot 12 therein which makes the braces applicable to bolsters of different thicknesses. The base 55 2 of the standard, and the horizontal portion of the braces are attached to the bolster 5 by the vertical bolts 11 and nuts 13. By reason of the slots 12, the braces 8 can be placed farther from or closer to the standard, and 60 the standard is thus applicable to bolsters of different widths and the standard is attached to the bolster by making small bolt holes and is not weakened by large mortises 65 through the bolts. The bolsters will last 70 much longer because there are no large mortised holes for accumulating water which would cause the bolsters to decay about the mortised holes. The standard is securely 75 attached to the bolster by reason of the base 80 2 and the braces 8 and the bolts described. The standard is further braced by the integral braces 14 which are integral with the body 1 and the base 2. The position of the braces 8, being swung inwardly at the bottom or lower ends, makes the braces more 85 efficient in holding the standard.

In the variation shown in Figs. 3 and 4, the braces are substantially double in strength and size of the braces 8 shown in 90 the previous views. The horizontal portions of the braces 15 are bifurcated so that the brace 15 will straddle the web braces 14 of the standard, as shown in Fig. 4. It will be seen that the braces 15 are substantially 95 twice as wide as the braces 8. The braces 15 are secured to the bolster 5 by bolts 9 and nuts 10, and also by the vertical bolts 11 and nuts 13. The braces 15 have also the slots 12, so that the braces 15 can be 100 moved closer to or farther from the body 1, of the standard, for the purpose of adaptation to the bolsters of different widths. The braces 15 are extended inwardly at the 105 bottom parts, for the purpose of making the braces more potent, and also for putting the horizontal bolts 9 out of the path of the vertical bolts 11.

The variations shown in Figs. 5, 6 and 110 7 include merely vertical flanges or lugs 16, in addition to the features of the corresponding braces in Figs. 3 and 4, the braces

being the same in every other respect as the 5
braces shown in Figs. 3 and 4. The up-
standing lugs 16 are integral with the hori-
zontal portions of the braces 18, and are
bolted to the web braces 14 by bolts 19 and
nuts 20, and slots 21 are made in the parts
16, so that the brace 15 will be adjustable on
the standard corresponding to the adjust-
ment provided by the slots 12.

10. What I claim is,—

1. A wagon standard comprising a body
and a base integral therewith and web
braces integral with said body and base,
braces for binding said base to a wagon bol-
ster each consisting of a vertical portion en-
gaging the side of the bolster and a slotted
horizontal portion engaging said base, vertical
bolts extending through said slots and
through said base and through the bolster
20 and nuts on said bolts binding said braces
and base and bolster together, and a hori-
zontal bolt and a nut therefor binding the
vertical portions of said braces to said bol-
ster.

25. 2. A wagon standard comprising a body
and a base therefor integral therewith
mounted on a bolster, front and rear braces
integral with said body and said base, braces
having horizontal portions engaging said
base and vertical portions engaging said
bolster, vertical bolts binding said braces
and base and bolster together, said braces
having slots for said bolts permitting ad-
justment to bolsters of different thicknesses,
35 the lower ends of said braces being extended
inwardly, and a horizontal bolt lying out of
the path of said vertical bolts for binding
said braces to said bolster.

3. A standard comprising an upright body

having a flat base mounted on a bolster and 40
front and rear braces integral with said
body and base, braces having vertical por-
tions engaging the sides of a bolster and
horizontal portions engaging said base, said
horizontal portions being bifurcated to en-
gage said base on both sides of each of said
first named braces and having slots therein,
vertical bolts projected through the bolster
and said base and through said slots and
nuts therefor, and a horizontal bolt binding 50
the vertical portions of said braces to the
bolster.

4. A standard for bolsters comprising an
upright body and a flat base integral there-
with and vertical front and rear braces in-
tegral with said body and base, detachable
braces having vertical portions engaging the
sides of a bolster and having bifurcated
horizontal portions engaging said base on
both sides of said front and rear braces and
having upstanding flanges engaging said
front and rear braces and said flanges hav-
ing horizontal slots therein, bolts projected
through said slots and through said front
and rear braces, the horizontal portions of 65
said detachable braces having slots therein,
bolts projected through the bolster and
through said base and through said slots
and nuts for said bolts, and a bolt binding
the vertical portions of said detachable
70 braces to said bolster.

In testimony whereof, I set my hand in
the presence of two witnesses, this 17th day
of August, 1912.

STEPHEN A. COWART.

Witnesses:

A. L. JACKSON,
R. B. RIDGWAY.
